(57) **CLAIM**

The ornamental design for a coffee tamper, as shown and described.

DESCRIPTION

FIG. 1 is a front and top perspective view of a coffee tamper, showing my design.

FIG. 2 is a rear and bottom perspective view thereof.

FIG. 3 is a front elevation view thereof, the rear, left, and right view being a mirror image thereof;

FIG. 4 is a top plan view thereof.

FIG. 5 is a bottom plan view thereof; and,

FIG. 6 is an enlarged view of detail 6 in FIG. 2.

The broken lines depict portions of the coffee tamper that form no part of the claimed design. The dot-dash broken lines in FIG. 2 and FIG. 6 depict the boundaries of the enlargements that form no part of the claimed design.

1 Claim, 6 Drawing Sheets
